UNITED STATES PATENT OFFICE

HARRY A. DOUGLAS, OF BRONSON, MICHIGAN

ELECTRIC SWITCH

Application filed November 11, 1931. Serial No. 574,272.

This invention relates to electric switches and has for its general object the simplification of the structure and operation thereof.

Among other objects, the invention aims to provide an improved rotary switch which is of particular utility as a rheostat for controlling the flow of electric current to a current consuming device such as the motor of a fan for an automobile heater.

10 The invention will be more fully explained in connection with the accompanying drawing in which—

Figure 1 is a longitudinal elevational view of a preferred embodiment of the invention;

15 Figure 2 is an end view of the structure of Figure 1;

Figure 3 is a longitudinal sectional view of the structure of Figure 1 being a section taken on the line 3—3 of Figure 2;

20 Figure 4 is a cross section taken on the line 4—4 of Figure 3 looking in one direction;

Figure 5 is a cross section taken on the line 5—5 of Figure 3 looking in the opposite direction; and

25 Figure 6 is a perspective view of some of the elements in separated relation.

Referring in detail to the figures of the drawing, I have shown a switch casing for my improved switch here represented by the 30 cylindrical metallic cup-shaped casing 1 which has an integral end wall 2 angular to the body of the casing and in a central aperture of which end wall is riveted a sleeve 3. The sleeve 3 is desirably exteriorly threaded to have screwed thereon a retaining ring 4. The casing is advantageously located on a mounting 5 which in one specific use that I now contemplate may be the dash board of an automobile. The switch is secured to the 40 mounting by passing the sleeve 3 through a suitable aperture in the mounting and clamping the portion of the mounting surrounding the aperture between the end wall 2 of the casing and the retaining ring 4 the latter being shown knurled around its periphery to facilitate tightening. To further insure that the switch casing will occupy only one rotative position with respect to the mounting,

45 I provide a lug 6 struck outwardly from the

end wall 2 and adapted to fall into a small hole 7 in the mounting.

In the present embodiment of the invention the sleeve 3 provides a bearing for one member of a rotor, in this instance, the metallic shaft 8 which is journaled in the sleeve and is adapted to freely rotate therein. For convenience in rotating the shaft 8, I have shown a handle 9 connected therewith as by being screwed into a transverse hole passing through the outer end of the shaft. Such handle permits the shaft to be readily assembled with the sleeve 8 by being passed through the interior of the casing 1 with the handle removed and thereafter the handle located in position as shown.

The rotor for the switch is inclusive of an insulating member represented in this instance by the floating fiber block 10 which is keyed to the shaft 8. The shaft 8 has an enlarged head 11 with a key way 12 cut transversely thereof to receive the fiber block 10. The head 11 prevents movement of the shaft outwardly of the casing. The shaft 8 is also desirably hollow and contains therein the coil spring 13 which presses the fiber block 10 outwardly of the key way 12, but is prevented by means later described from disengaging the fiber block from the key way. Thus the fiber block 10 has resilient movement in the key way longitudinal of the shaft 8. To enhance the action of the spring 13, the fiber block 10 desirably has a short tail portion 14 which enters the hollow shaft 8 beyond the key way 12 and engages the spring 13 to compress the spring when the block and shaft are held in interengaging position.

Upon its side opposite the tail portion 14 the fiber block 10 has a reduced key portion 15 which enters a similarly shaped slot 16 in a metallic switch member 17. The switch member 17, insulating block 10 and shaft 8 are thus keyed to rotate together and the switch member is insulated from the shaft. To locate these parts in assembled position, the portion 15 of the block 10 passing through the slot in the switch member is continued in a further reduced portion 18 which is journaled in a central circular aperture 19 of a

closure for the switch casing here shown as the insulating disc 20. The disc 20 may be secured to the casing as by having prongs 21 of the casing clinched over the disc.

5 In the illustrative construction, the insulating disc 20 constitutes a contact carrier for a plurality of fixed circumferentially disposed metallic contact members mounted thereon and which are adapted to be selectively engaged by the switch member 17, means being provided for maintaining the switch member in continuous engagement with one of the contact members. Such contact members are typified at 22, 23, 24, 25 and 10 26, each of these terminating within the casing in a dome shaped contact surface 27 adapted to seat in a depression 28 in the face of the switch member 17. One of the contact members, in this instance, the member 22 15 rivets to the insulating disc 20 a metallic plate 29 which has a ring shaped portion 30 margining the aperture 19 in the insulating disc 20, the inner periphery of the ring being advantageously continued to form a lip 20 30* which provides a bearing surface for the continuation 18 of the block 10. The ring 30 thus constitutes a central continuation of the contact 22 and the contacts 23, 24, 25, and 26 are complementary thereto.

25 30 In accordance with this exemplification of my invention, the switch member 17 is provided with two contact portions, one of these portions being represented here by an angular toe 31 which rides on the ring portion 30 35 of the plate 29 and the other contact portion by the portion of the switch member containing the depression 28. The toe 31 serves the double purpose of maintaining the switch member 17 in continuous electrical engagement with the contact member 22 and at the same time provides a fulcrum upon which through the action of the spring 13 the switch member is pressed into engagement with the central contact and with one of the complementary contact members 23, 24, 25 or 26, 40 when the shaft 8 is appropriately rotated, the depression 28 contributing to a snap action of the switch.

The toe piece 31 terminates in a flat surface 50 31* of substantial proportions transversely of the switch member 17 so as to maintain the switch member substantially perpendicular to the contact members so as to afford good electrical connection with the plate 30 and 55 also to maintain the switch member substantially parallel with the plate to prevent it from dropping between the contacts. The switch member 17 is desirably flared at its outer end to form a segmental portion 17* 60 embracing a substantial arc of the circle traveled by the switch member, so that the switch member will readily ride from one contact member onto the next. Curved cam surfaces 17* 65 are provided at the ends of the segmental portion 17* to facilitate this riding action

of the switch member. Since, as shown, the key portion 15 of the block is elongated transversely of the switch member 17, the switch member may oscillate slightly on an axis which is transverse to the shaft 8 and which passes between the depression 28 and the toe 31 to insure that the switch member will contact with both the plate 30 and the selected complementary contact.

70 The contact member 22 may be connected, by means of the binding screw 32, with a conductor leading to a suitable source of electric current. When the shaft 8 is turned to bring the switch member 17 into rotative position such that not only is the toe 31 in contact with the ring 30 but also the contact member 22 is seated in the depression 28 of the switch member, then the switch is in off position, no electrical connection being then made between the contact 22 and any of the other contacts.

75 It is desirable that the shaft 8 may be rotated in only one direction from the position last described and to accomplish this I have shown a stop 33 against which a finger continuation 34 of the fiber block 10 abuts, as best shown in Figure 5. The shaft 8 may be then rotated, however, to electrically connect the contact 22 through the plate 29 with the contact 23. The contact 23 may 80 have connected thereto, by means of one of the binding screws 32, a conductor leading to a motor (not shown) where the invention is employed to control the speed of a fan. With the contact members 22 and 23 thus 85 electrically connected by the switch member 17, the fan will operate at full speed in accordance with well known principles of operation of such devices.

90 When it is desired to reduce the speed of the fan, the shaft 8 may be turned to cause the switch member 17 to electrically connect the contact member 22 and the contact member 24. The contacts 24, 25 and 26 95 are connected with the contact 23 through an element such as the high resistance wire 35, the contacts 24, 25 and 26 tapping successively 100 a greater number of turns of the resistance so as to increase the resistance of the circuit through the motor as the switch member 17 105 may be placed in contact successively with the contact members 24, 25 and 26. When the switch member 17 is in engagement with the contact member 26, the finger 34 of the block 10 then abuts the stop 36 which prevents the 110 switch member from being further rotated in its last direction of rotation. Thus the switch cannot be turned directly from the off position to include the resistance 35 in circuit.

115 The stops 33 and 36 may be conveniently formed by being struck out of the body of the casing 1.

120 Having described one embodiment of my invention, I claim:

100

105

110

115

120

125

130

1. In an electric switch, the combination of a casing; a hollow metallic shaft journaled in one end of the casing; a fiber block keyed to rotate with the shaft and movable longitudinally thereof; a coil spring housed by the shaft and pressing the fiber block longitudinally of the shaft; a metallic switch member fulcrumed on said fiber block and keyed to rotate therewith; an insulating disc forming a closure for the casing at its end opposite the shaft; a central aperture in said disc; a continuation of the fiber block journaled in said aperture; an annular metallic contact margining said aperture; a toe on said switch member engaging said annular contact in all positions of the switch member; and complementary contacts radially disposed on said disc and selectively engageable by the switch member upon rotation by the shaft.

2. In an electric switch, the combination of a casing; a sleeve fixed in one end of the casing; a hollow metallic shaft journaled in said sleeve; an enlarged head on said shaft within the casing and abutting said sleeve; a transverse keyway in said head; a rectangular fiber block disposed transversely of the shaft in said keyway, said block having a tail portion extending into the bore of said shaft; a coil spring housed in said shaft and pressing upon the tail portion; a rectangular key portion on said block oppositely disposed from said tail portion; a metallic switch member disposed transversely of said block and having a rectangular slot therein snugly receiving said key portion of the block therethrough, said switch member having an angular toe closely adjacent said slot upon one side of the block and being flared at its end upon the other side of the block to form a segmental portion farther removed from the block than the said toe; an insulating disc forming a closure for the casing at its end opposite the sleeve; a central aperture in said disc; a continuation of the fiber block journaled in said aperture; an annular metallic contact margining said aperture and engageable by said toe in all positions of the switch member; and complementary contacts radially disposed on said disc and selectively engageable by the segmental portion of the switch member upon rotation by the shaft.

In witness whereof, I hereunto subscribe
55 my name.

HARRY A. DOUGLAS.
